UNITED STATES PATENT OFFICE.

SAM J. SILVERSTEIN, OF MOUNT VERNON, NEW YORK.

DESIGN FOR A COMBINATION POCKETBOOK AND ANIMAL BRUSH.

Application filed November 30, 1928. Serial No. 29,067. Term of patent 3½ years.

To all whom it may concern:

Be it known that I, SAM J. SILVERSTEIN, a citizen of the United States, residing at Mount Vernon, in the county of West Chester and State of New York, have invented a new, original, and ornamental Design for Combination Pocketbooks and Animal Brushes, of which the following is a specification, reference being had to the accompanying drawing, forming part thereof.

I claim:

The ornamental design for a combination pocketbook and animal brush, as shown.

SAM J. SILVERSTEIN.
